OF BLAIR, NEBRASKA.

COW-TAIL HOLDER.

1,257,739.

Specification of Letters Patent. Patented Feb. 26, 1918.

Application filed July 30, 1917. Serial No. 183,535.

To all whom it may concern:

Be it known that we, SOFUS E. RASMUSSEN, a subject of Denmark, residing at Beresford, in the county of Union and State of South Dakota, and LAUGE L. KIRKEGAARD, a citizen of the United States of America, residing at Blair, in the county of Washington and State of Nebraska, have invented certain new and useful Improvements in Cow-Tail Holders, of which the following is a specification.

Our invention relates to improvements in cow tail holders having a clasper to releasably engage around a cow's hind leg above the gambrel joint, and a clamp to simultaneously grip and hold the brush of her tail during the operation of milking; and the objects of our improvements are, first, to provide means for utilizing the secured brush of the cow's tail as a locking key to secure the separable ends of an elastic leg clasper; second, to provide an elastic leg clasper normally standing wide open to freely receive the leg of the cow and that can be opened and closed with a minimum of movement of its free opposed ends, thereby conserving the body of the clasper against rupture; third, to provide a hinged locking hook, fastened by engaging the brush of the tail, that may be swung into or out of the mouth of the clasper; fourth, to supply a suitable stop to limit the swing of the locking hook and set it in alignment with a loop on the opposite free or swinging end of the clasper; and fifth, to provide the free or coupling ends of the leg clasper with suitable integral handles, all bent from a single piece of wire, to supply a suitable bearing with end collars on one, and the requisite loop on the opposite handle to receive the locking hook. Which objects we attain by the mechanism and construction illustrated in the accompanying drawing, in which—

Figure 1 is a top view showing the holder applied, the leg and tail being indicated by dotted lines; Fig. 2, a vertical section on the broken line 2 of Fig. 1; Fig. 3, a vertical cross-section on the broken line 3 of Figs. 1, 2 and 4; Fig. 4, an outside elevation of the holder when closed; and Fig. 5, a top view of the opened holder, with the swinging locking-hook turned out of the mouth of the clasper, ready for placing it on the leg. In all of which views similar numerals refer to like parts.

A piece of spring wire has an intermediate portion bent to form the curved base 4 which, with an integral branch 5 and a like opposite branch 6, disposed as shown, form the elastic clasper to close around a cow's leg. The outer ends of these branches normally stand apart, as shown in Fig. 5, to receive and close around the leg L, as shown and indicated in Fig. 1. Integral adjacent straight portions of the wire form the respective bases 7 and 8 of the handles, for manipulation, which are disposed at divergent angles from the swinging ends of the branches of the clasper, to stand parallelly with each other when the clasper is closed, as shown in Fig. 1. Further continuous adjacent portions shaped by downwardly disposed return bends form the outer ends of the handles. The return part 9, disposed parallelly with and spaced below the handle base 8, has its inner end portion bent upwardly and to form the terminal fastening eye 10 closed around the inner end of the base at its juncture with that branch of the clasper. This forms a double or reinforced handle and an open loop disposed in a vertical plane to receive therethrough the fastening hook mounted on the opposite handle.

The return reinforcing part 11 of the opposite handle has an intermediate portion looped upwardly and bent around the center of the base 7 to form the collar 12 thereon. The remaining end portion is bent to form the stop bar 13 spaced parallelly below and laterally toward the opposite handle; then the inner end is bent to form the terminal fastening eye 14 closed around the inner end of this base at its juncture with this branch, the same as for the opposite handle. That part of this base between the central collar 12 and the end fastening eye, serves as a pivotal or bearing bar 15 to carry the locking hook.

The swinging locking hook consists of a single piece of wire; an intermediate portion is bent doubled upon itself, and this doubled portion is bent flatwise, or in a plane at right angles to the plane of the doubling bend, to form the double-width engaging-curve 16 and point of the hook. One fold of the engaging-curve is extended tangentially and straight to form the inner leg 17 of the forked shank of the hook; this shank leg terminates in the eye 18 closed around the inner end of the bearing-bar. 110

The opposite fold is extended in a reversely-curved outer leg 19 ending in the eye 20 closed around the outer end of the pivotal bearing bar. These eyes that hinge the hook 5 on the pivotal bar are spaced apart so that they normally cover a distance greater than the length of the bar between the collar 12 and the fastening eye 14; therefore, the hook is frictionally held at any position to 10 which it may be turned on its pivotal bar.

Swinging the hook downwardly toward the opposite handle, it is stopped by the bar 13 in position to close through the loop of said handle when the clasper is closed; thus 15 closed, the brush T of the cow's tail is inserted in the hook to serve as a key preventing the withdrawal of the hook from the loop, to lock the clasper on the leg and simultaneously fasten the tail against 20 switching. Pressing the handles of the locked clasper toward each other, the brush of the tail is released from the hook, which will then be withdrawn from the loop handle as the clasper is opened. The hook is 25 then swung out of the mouth of the clasper leaving it clear for application or removal from the leg.

We claim:

1. A cow tail holder, comprising a spring-metal curved leg clasper having opposed coupling ends normally standing spaced, a loop on one coupling end, a hook on the opposite coupling end to protrude through said loop, when the clasper is closed, to engage the brush of a cow's tail inserted in the hook and against the outside of the loop, whereby the hook is gripped against the brush of the cow's tail by the resiliency of the clasper closed around the cow's leg and 40 the gripped brush of the tail serves as a removable key to prevent withdrawal of the hook from the loop.

2. A cow tail holder, comprising a curved elastic leg clasper having opposite end 45 branches normally standing apart at their outer coupling ends which are adapted to be elastically swung toward each other to close the clasper, manipulation handles on the swinging ends of said branches, a loop

in one handle, a laterally standing hook on 50 the opposite handle to protrude through said loop, when the clasper is closed around a cow's leg, to releasably engage the brush of the cow's tail which prevents withdrawal of the hook from said loop. 55

3. A cow tail holder, comprising a curved elastic leg clasper having coupling ends disposed to normally stand apart to form an open mouth to the clasper, manipulation handles on said coupling ends, a loop in one 60 handle, a hook hinged on the opposite handle to swing out of or into the open mouth of the clasper and adapted to protrude through the loop in the first mentioned handle when the clasper is closed. 65

4. A cow tail holder, comprising a U-shaped leg clasper of spring wire, manipulation handles formed by looped extensions of the branches of the U, a hook hinged on one side of the loop of one handle to 70 swing laterally into and out of the space between the handles, and a stop consisting of the opposite side of said loop disposed to limit the swing of the hook to set it in alignment to protrude through the loop of 75 the opposite handle when the handles are swung toward each other to close the clasper.

5. A cow tail holder, comprising an open loop of spring metal to form a leg clasper having its closing ends normally standing 80 spaced to form a receiving mouth, manipulating handles on the closing ends of the clasper, a loop on one handle, spaced collars on the opposite handle, a hook having an elastic forked shank the branches having 85 hinging eyes closed around the handle between said collars, said eyes spaced to elastically bear against said collars to frictionally support the hook and the hook disposed to swing into position to protrude through 90 said loop when the clasper is closed and swing out of the mouth when the clasper is open.

In testimony whereof we hereunto affix our signatures.

SOFUS E. RASMUSSEN.
LAUGE L. KIRKEGAARD.
